UNITED STATES PATENT OFFICE.

HENRY E. HURTZ, OF HAWTHORNE, NEW JERSEY.

TEXTILE REED.

1,420,262.

Specification of Letters Patent. Patented June 20, 1922.

Application filed December 23, 1920. Serial No. 432,763.

To all whom it may concern:

Be it known that I, HENRY E. HURTZ, a citizen of the United States, residing at Hawthorne, in the county of Passaic and State of New Jersey, have invented certain new and useful Improvements in Textile Reeds, of which the following is a specification.

This invention relates to improvements in reeds for use in the manufacture of textile goods.

The primary object of the invention is the provision of a textile reed comprising a plurality of specially designed dents, the thread faces of which are arcuated to prevent undue wear thereupon.

A further object of the invention, is the provision of a reed dent for use in the manufacture of textiles, such as silk, which forms a cylindrical segment of even cross section throughout, and has an arcuate wearing face.

A further object of the invention is the provision of a textile reed in which the dents are of such special construction, and arrangement, as to allow a minimum of wear thereupon; thus effecting a practical, economical, and durable structure.

Other advantages of the improved textile reed will be apparent during the course of the following detailed description.

In the accompanying drawings forming a part of this specification, and in which like reference characters designate like parts throughout the same,

Figure 1 is a fragmentary side elevation of a front warp reed.

Figure 2 is a cross section taken on the line 2—2 of Figure 1, and showing the relation of textile threads to the dents of the reed.

Figure 3 is a fragmentary side elevation of a crossing reed.

Figure 4 is a cross-sectional view taken on the line 4—4 of Figure 3.

Figure 5 is a plan view of the manner in which a warp is formed from a plurality of textile threads.

Figure 6 is a cross sectional view of a broad silk reed showing the relation of the threads of a warp to the dents thereof.

In the drawings, wherein for the purpose of illustration is shown a preferred embodiment of my invention, the dot and dash line A designates a creel having a plurality of spools B mounted thereon, throughout its

length, each one of which spools has a thread 55 C thereon.

In the manufacture of textile goods, such as silk goods, it is an essential to first prepare a warp of the proper design and width from which such goods can ultimately be 60 manufactured. In the production of broad silks and ribbons, it is sometimes necessary to use as many as five thousand spools upon a single creel. This obviously requires a creel of considerable width, and in order to bring 65 the threads to the proper width upon the warp, reeds must be used.

Colored goods, or those of special design require an accurate arrangement of threads upon the warp, and in order to insure this, 70 and to facilitate such adjustment, a crossing reed D, relatively smaller in width than the width of the creel A is used; which reed also facilitates in the bringing together of the threads for disposal upon the warp. 75 However, before their disposition upon the warp, the threads C are required to be arranged in spaced relation to form a warp of proper width. To effect such arrangement, a front warp reed E is used; the same being 80 relatively narrower in width than the width of the crossing reed D.

The reeds, as used in the manufacture of silk goods today, employ dents which are substantially rectangular in cross-section. 85 Due to the tensioning of the silk threads upon the dents of the reeds D and E, it has been found that the employment of rectangular dents requires the constant care and attention of one experienced in the spinning of 90 textile warps. This fact has been brought about primarily because nicks are worn in the edges of the rectangular dents, due to the tensioning of the thread thereupon. The thread is thus prevented from riding longitudinally upon the dents and upon doing so, the thread riding thereupon is invariably broken. This necessitates an entire stopping of the warp mill, to repair the particular thread, and may some time cause the entire 95 replacement of a new reed. The dent as used upon the improved type of reed illustrated in the drawings accompanying this specification has been designed primarily to do away with the wearing of nicks in the 100 dent face, thus insuring the durability and effectiveness of the improved reed as illustrated in the drawings.

The improved dent 15 comprises a cylindrical segment, of even cross section throughout. Each of the segments 15 has an arcuate or convex face 16, which extends throughout the length of the dent; and a rear surface of back 17, which is a flat or plane surface. It is to be distinctly understood that the dent 15 is solid throughout its length, and this fact, together with the fact that 10 the wearing or arcuate surface 16 is curved insures a permanency of such a dent over the rectangular shaped dent now in common use.

The front warp reed E is provided with a plurality of the dents 15, each one being 15 a solid spherical segment, and is secured near each longitudinal edge to the binding wires 20 as in the ordinary reed construction, by means of springs and spacing wires 21. The spacing wires 21 are uniform in 20 thickness, and the space 22, between any two adjacent dents 15, is equal to the width of this spacing wire 21, as is clearly shown in Figure 1 of the drawings. The spacing wires 25 are spiral in shape and extend from one side of the dent 15 to the other, for the purpose of securely binding the same to the binding wires. By this arrangement, the spaces 22 throughout the length of the reed are uniform in width, thus insuring that the 30 dents 15 will be equally spaced upon the reed E. The binding wires 20 are rigidly secured about, and welded to the side pieces 23 and 24 of the reed structure E. End pieces 25 are then soldered or welded to the 35 side pieces 23 and 24 and have embedded in them, the ends of the dents 15 which extend beyond the binding wires 20. Thus a staple, secure and well balanced reed structure is secured, employing the improved dent 15.

40 The arrangement of the dents 15 within the frame structure of the reed E is of prime importance, due to the manner in which the threads C are received from the crossing reed D, incidental to their formation as a warp. As illustrated in Figure 5, the side 45 10 of the reed E faces the crossing reed D. From observation of the threads C, as shown in Figures 2 and 5 of the drawings, it can readily be seen that the threads C nearest 50 to the side pieces 23 and 24 of the reed structure E, enter at an acute angle to the longitudinal run of the reed E; and which angle increases for each succeeding thread C as the center of the reed E is approached, until 55 the center thread 27, intersects the longitudinal run of the frame E at substantially a right angle. This necessitates considerable wear upon the part 28 of the convex face 16 adjacent the side 10 of the reed E, which 60 faces the crossing reed D. It can, of course, be seen that the wear will be greatest upon the dents 15 adjacent the side pieces 23 and 24, since the change of angle in the threads C, and consequently the tensioning due there- 65 to is greatest upon those threads. However

the surface 28, which in reality is part of the convex surface 16, presents a rounded surface for the thread C to glide over and there will consequently be no possibility of nicks, or grooves being worn in the surface of the dent, and which ordinarily causes breaking of the threads C.

The life of the reed E is of course determined by the wear upon the faces 16 of those dents adjacent the side pieces 23 and 24, 70 since the dents nearest the center of the reed E receive practically no wearing from the threads C. The front warp reed E is ordinarily centrally disposed with respect to the crossing reed D, and this fact, taken into 75 consideration with the necessity of a front warp reed E for properly securing the width of a warp, renders it necessary that one-half of the dents 15 upon one side of the reed E, be placed with their convex faces 16 facing 80 the center of the reed E, while the other half of the reed E has the dents 15 similarly positioned. Thus the convex faces 16 of the dents 15 upon one side of the frame face the convex faces 16 of the dents 15 upon the 85 other side of the reed E.

When the faces 28 of the convex surface 16 of the dents 15 have been worn down to render the side 10 of the reed E of no further value, the reed is reversed, and the side 11 90 of the reed E is disposed toward the crossing reed D, thus reversing the position of the dents 15, and the surfaces 29 of the convex faces 16 will now directly receive the tensioning of the threads C, since they have heretofore received no wear whatsoever, as can be readily seen from an observation of Figure 2 of the drawings.

The crossing reed D, as illustrated in Figures 3 and 4 of the drawings is altogether 105 similar to that of the front warp reed, and comprises a plurality of dents 15 arranged in spaced relation, by a spacing spring 35, engaging either side of the dents 15 tying them rigidly to the binding wires 36. The side pieces 37 and 38 of the crossing reed D, similarly support the binding wires 36, and a top piece 39, is welded or otherwise secured to the side pieces 37, 38, and to the ends of the dents 15, to form a rigid crossing frame 110 D. The arrangement of the dents 15 within the frame of the crossing reed D is altogether similar to that described for the front warp reed E, and comprises one half of the dents 15 having their convex or arcuate faces 115 16 facing the center of the reed D, while the other half are similarly disposed; thus one half of the frame D have one half of the convex faces 16 facing the convex faces 16 of the other half.

The crossing reed D is provided for arranging the threads to suit the particular color or design of the broad silk or ribbon, or other textile goods to be woven, and is provided primarily for the purpose of put- 120 125 130

ting the cross in the warp. In order to effect this, the crossing reed D is provided with metal inserts 40, welded, or otherwise secured within the alternate spaces 41, as 5 provided by the dents 15. The inserts 40 are welded to a face 16 of one of the dents 15, and welded to its adjacent dent 15 on the flat surface 17 thereof. Thus the spaces 41 of the reed D are subdivided throughout 10 their height, since there are generally a number of the inserts 40 within the space 41. The inserts 40 are arranged within the alternate spaces 41 in parallel alignment with the top 39 of the crossing reed D, and in fact 15 divide the crossing reed D into a plurality of subdivisions to effect the crossing in the warp. The side 43 which ordinarily faces the creel A primarily receives the threads C which wear upon the surfaces 44 of the 20 convex faces 16. The crossing reed D is reversible, similar to the reed E, and the side 45 can be positioned to face the creel A, in which event the surfaces 46 of the dents 15 will primarily receive the tension, and friction 25 of the threads C.

A broad silk reed F is illustrated in Figure 6 of the drawing and is formed altogether similar to the framework of the reeds D and E. However, the reed F is not used 30 in the spinning of a warp, but is used on a loom in the actual weaving of a textile goods. Its purpose is to provide an accurate 35 spacing of the threads C as they come from the warp, and is used upon a loom intermediate the warp, and the actual goods which are being woven. The tendency of goods, such as silk, which are in the weaving process, is to shrink the threads C, which is in reality caused by operation of the shuttle. 40 As illustrated in Figures 6 of the drawings, the threads C which are being unwound, from the warp and entering the broad silk reed F, through the side 50 thereof, are arranged in parallel relation, since they come 45 directly from the warp. However, as before stated, the shuttle tends to shrink the goods, somewhat, and produces an inclination of the threads C upon the side 51 of the broad silk reed F, as is clearly shown in Figure 6 of the drawings. Thus a warp 38 50 inches in width will sometimes shrink to 37 inches or $37\frac{1}{4}$ inches in width. The broad silk reed F is therefore obviously necessary. Since the tendency of the threads C is to 55 converge after leaving the broad silk reed F, it follows that the operation is the exact reverse of that required for the swinging of the threads C upon the warp. The dents 15 in the reed are exactly similar to the dents 60 employed in the front warp reed and the crossing reed. The only difference lies in the arrangement of the dents within the reed structure. In this case, the convex faces 16 of one half of the reed F are provided to 65 face the side piece 53 of one side of the

frame F, while the other half of the dents 15 have their convex faces facing the other side piece 54 of the other side of the broad silk reed F. Thus the arrangement is exactly reverse to the dents in the reeds 70 D and E. Since the threads C approach the reed F in parallel relation, it follows that the center or highest portion of the arcuate faces 16 receives the tension of the thread and the greatest wear will be upon this portion. 75 However, due to the fact that the threads are inclined to the center of the frame F after they leave the frame, there will be no surface for the threads C to rub against, consequently no nicks will be formed 80 in the dents 15. It is otherwise when the rectangular shaped dents are used, for then nicks are formed in the upper edges thereof.

From the foregoing description, it can readily be seen that a dent has been provided 85 for use upon reeds, adapted for use in connection with textile manufacture, and particularly in the silk industry.

It is to be understood that the form of my invention herewith shown and described 90 is to be taken as a preferred example of the same, and that various changes in the shape, size and arrangement of parts may be resorted to, without departing from the spirit of the invention or the scope of the subjoined 95 claims.

I claim:

1. As an article of manufacture, a dent for reeds comprising a cylindrical segment of uniform cross section throughout, and having 100 a longitudinal convex surface and a longitudinal plane surface.

2. As an article of manufacture, a dent comprising a solid cylindrical segment of uniform cross section throughout, and having 105 a longitudinal arcuate wearing surface, and a longitudinal flat back surface.

3. In a textile reed, the combination, of a plurality of dents, each of said dents being a solid cylindrical segment of uniform cross 110 section throughout its length having a longitudinal arcuate surface, and a plane surface, and means for rigidly fastening said dents to form a reed.

4. In a textile reed, the combination, of a plurality of dents, each of said dents comprising a cylindrical segment of uniform cross section throughout, and having an arcuate surface, and means for securing said dents to form a reed, in such manner that 120 all of the arcuate surfaces of said dents on one side of the reed, face the arcuate surfaces of the other of said dents.

5. In a textile reed, the combination, of a plurality of dents, each one of said dents 125 comprising a solid cylindrical segment of uniform cross section throughout, and having a longitudinal arcuate wearing surface, and a plane back surface, and means for rigidly securing said dents in spaced rela- 130

tion to form a reed, one half of said dents upon one side of the reed having their convex surfaces facing the convex surfaces of the other half of said dents upon the other 5 side of said reed.

6. In a crossing reed, the combination, of a plurality of dents, each of said dents being a cylindrical segment of even cross section throughout, and having an arcuate longitudinal surface, and a longitudinal plane surface; means for rigidly fastening the ends of said dents to form a reed, the arcuate surfaces of the dent facing the center of 10 said reed; and means for fastening certain

adjacent dents together intermediate the 15 ends thereof.

7. A textile reed comprising a frame, a plurality of dents having a plane surface and a convex surface merging into said plane surface, and means for fixing said dents in said frame so that a convex surface of one faces the plane surface of its adjacent dent to provide a space intermediate adjacent dents, the width of which space at the longitudinal center of the adjacent dents 20 is less than the width of the space at the longitudinal marginal edges of said dents. 25

HENRY E. HURTZ.
